UNITED STATES PATENT OFFICE.

JAMES L. BROWN, OF INDIANHEAD, MARYLAND, ASSIGNOR TO THE UNIVERSAL ORDNANCE AND POWDER CO., OF WASHINGTON, DISTRICT OF COLUMBIA.

FUSE FOR PROJECTILES.

SPECIFICATION forming part of Letters Patent No. 791,873, dated June 6, 1905.

Application filed November 21, 1902. Renewed May 9, 1905. Serial No. 259,624.

To all whom it may concern:

Be it known that I, JAMES L. BROWN, a citizen of the United States, residing at Indianhead, in the county of Charles and State of Maryland, have invented certain new and useful Improvements in Fuses for Projectiles, of which the following is a specification.

The present invention relates to an improved fuse for projectiles, and has special reference to a fuse adapted to be used upon explosive projectiles, and is adapted to cause the explosion of the explosive therein a short time after the projectile contacts an object, so as to not cause the same to explode before entering the object, but after it has nearly passed through the object.

Another object of this invention is the provision of a novel construction of fuse for explosive projectiles which under ordinary circumstances is held in "safety" position by a novel means which when placed in the gun and after the discharge of the gun the backward shock or the blow of discharge on the base of the projectile causes the firing-pin to set back, releasing the safety means, which is thrown out by centrifugal force, so as to give free access of the firing-pin to the percussion-cap, which is exploded by means of a loosely-mounted spherical plunger, which is thrown forward to contact the firing-pin as the projectile is impeded in its forward movement by contact with any object, thus causing the explosion of the projectile shortly after such contact, the time being regulated by the distance the loosely-mounted spherical plunger has to travel after the projectile strikes.

To attain these objects, the invention consists of novel features of construction and combination of parts, substantially as set forth and claimed.

In the accompanying drawings, Figure 1 is a sectional view of the base end part of a projectile with my fuse shown in section with its parts at safety. Fig. 2 is a similar view with the fuse in the position it assumes when the projectile is traveling. Fig. 3 is a similar view with the parts of the fuse in the position they assume after the projectile has struck the

object. Fig. 4 is a cross-section of the fuse, said Fig. 4 showing more particularly the safety device for holding the firing-pin away from the cap. Fig. 5 is a perspective view of the firing-pin.

Referring to the drawings, A designates the threaded casing in the butt of the projectile, in which is adapted to be secured by means of screw-threads the fuse B. The fuse consists, substantially, of the tubular casing 1, provided with the sealing-cap 2, which provides the cylindrical chamber 3, in which is loosely mounted a spherical hammer or plunger 4. Adapted to fit within the upper end of the casing and be held by means of the lugs 5 is the cylindrical plug 6, which is provided with a central channel 7 and a plate 8, in which is provided a small opening 9, the fulminating cap-socket 10, and the upper portion 11 of the channel 7, in which is adapted to loosely fit the firing-pin 12, which is adapted to strike the fulminating-cap 13.

Pivottally mounted at one end in the grooves 14 of the plug are the two segmental arms or wings 15, which are provided upon their lower inner edges with the segmental grooves 16, which are adapted when the fuse is at "safety" to receive the rim of the cup 17, carried intermediate of the ends of the firing-pin. Resting upon the interior shoulder 3^a of the cylindrical chamber 3 is a circular disk 19, provided with a central opening through which is adapted to project the stem 20 of the firing-pin, a coil-spring 18 surrounding the stem within the disk 19 and a cup 17 of the firing-pin, so as to normally exert a tension against the upper face of the disk 19 to cause the cup 17 to be normally held in engagement with the groove 16 of the arms or wings 15.

From the foregoing description, taken in connection with the drawings, it will be seen that while the projectile is at rest the parts of the fuse assume the position shown in Fig. 1; but as soon as the gun is discharged the force thereof causes the firing-pin of the fuse of the projectile to slightly compress the spring 18, thus moving and releasing the cup 17 from the grooves of the wings 15, so that the

centrifugal force given the projectile by means of the rifling of the gun will cause the free ends of the wings to move outward, thus allowing the firing-pin to have access to the fulminating-cap. As soon as the projectile contacts the object the spherical plunger is caused to move forward in the chamber of the tubular casing and by such impedance of the projectile is thrust against the end of the stem 10 of the firing-pin, causing the firing-pin to contact the fulminating-cap of the projectile and explode the projectile long enough after the contact of the projectile to allow the same to pass through the armor plate. It will thus 15 be seen that the fuse for projectiles is provided which is readily applicable to the projectiles now in use and which will at all times cause the explosion of the projectile shortly after contact notwithstanding at what angle 20 the projectile contacts the object, as the loosely-mounted spherical plunger will always be given a movement which will strike the firing-pin.

What I claim as new is—

25 1. In a fuse, the combination of a socketed casing, a fulminating-cap, means for exploding the fulminating-cap, automatically-operated means for holding the said exploding means from contact with the fulminating-cap,

30 and a spring for holding the said exploding means in engagement with said automatically-operated means, adapted to be compressed or set back, due to the firing of the gun to release the exploding means from engagement with 35 the automatically-operated means.

2. In a fuse, the combination of a socketed casing, a fulminating-cap, means for exploding the fulminating-cap, centrifugally-operated means for holding the said exploding 40 means from contact with the fulminating-cap, and a spring for holding the said exploding means in engagement with said centrifugally-operated means, adapted to be compressed or set back, due to the firing of the gun to release 45 the exploding means from engagement with the centrifugally-operated means.

3. In a fuse the combination of a fulminating-cap, firing-pin, separate means for striking the firing-pin, automatically-operated 50 means locking the firing-pin against forward motion, and means on said firing-pin causing the firing-pin to engage the automatically-operated means to lock said automatically-operated means until the firing-pin releases 55 the automatically-operated means when operated upon by the setback due to the firing the gun.

4. In a fuse, the combination of a casing, a plunger mounted therein so as to be capable 60 of acting forwardly upon lateral impact, a fulminating-cap, a firing-pin, automatically-operated means locking the firing-pin against forward motion, and means on said firing-pin locking said automatically-operated means un-

til released by the setback due to the firing of 65 the gun.

5. In a fuse, the combination of a fulminating-cap, a firing-pin, separate means for striking the firing-pin, centrifugally-operated means locking the firing-pin against forward motion, and means on said firing-pin causing the firing-pin to engage the centrifugally-operated means to lock said centrifugally-operated means until the last-mentioned means is released by the setback due to the firing of 75 the gun.

6. In a fuse, the combination of a casing, a plunger mounted therein so as to be capable of acting forwardly upon lateral impact, a fulminating-cap, a firing-pin, centrifugally-operated means locking the firing-pin against forward motion, and means on said firing-pin locking said centrifugally-operated means until released by the setback due to the firing of 80 the gun. 85

7. In a fuse, the combination of a casing, a loosely-mounted spherical plunger mounted therein, a fulminating-cap, a firing-pin, centrifugally-operated means locking the firing-pin against forward motion, and means on said firing-pin locking said centrifugally-operated means until released by the setback due to the firing of the gun. 90

8. In a fuse the combination of a casing, a plunger mounted therein so as to be capable 95 of acting forwardly upon lateral impact, a fulminating-cap, a firing-pin, centrifugally-operated means adapted to be engaged by the firing-pin to form a lock against the movement 100 of said means, said centrifugally-operated means preventing the forward motion of the firing-pin, and means mounted on the firing-pin for holding the firing-pin in locked engagement with the centrifugally-operated 105 means, the firing-pin releasing the centrifugally-operated means by the setback due to the firing of the gun.

9. In a fuse, the combination of a casing, a loosely-mounted plunger mounted therein, a fulminating-cap, a firing-pin, centrifugally-operated means adapted to be engaged by the firing-pin to form a lock against the movement 110 of said means, said centrifugally-operated means preventing the forward motion of the firing-pin, and means mounted on the firing-pin for holding the firing-pin in locked position with the centrifugally-operated means, the firing-pin releasing the centrifugally-operated means by the setback due to the firing 115 of the gun. 120

10. In a fuse, the combination of a casing, a loosely-mounted spherical plunger mounted therein, a fulminating-cap, a firing-pin, centrifugally-operated means adapted to be engaged by the firing-pin to form a lock against 125 the movement of said means, said centrifugally-operated means preventing the forward motion of the firing-pin, and means mounted

on the firing-pin for holding the firing-pin in locked position with the centrifugally-operated means, the firing-pin being operated to release the centrifugally-operated means by the 5 setback due to the firing of the gun.

11. In a fuse the combination of a casing, a plunger mounted therein so as to be capable of acting forwardly upon lateral impact of the fuse, a plug mounted in one end of the 10 casing, a fulminating-cap mounted in the plug, a firing-pin mounted in the plug, centrifugally-operated means locking the firing-pin against forward movement in the plug, and means on the firing-pin locking the centrifugally-operated means until released by the setback due to the firing of the gun.

12. In a fuse, the combination of a casing, a plunger loosely mounted therein so as to be capable of acting forwardly upon lateral impact, a plug mounted in one end of the casing, 20 a fulminating-cap mounted in the plug, a firing-pin mounted in the plug, centrifugally-operated means locking the firing-pin against forward movement in the plug, and means on the firing-pin locking the centrifugally-operated means until released by the setback due to the firing of the gun.

13. In a fuse, the combination of a casing, a plunger mounted therein so as to be capable 30 of acting forwardly upon lateral impact, a plug mounted in one end of the casing provided with a central channel therethrough, a fulminating-cap mounted in the plug in one end of said channel, a firing-pin slidably mounted within said channel, centrifugally-operated means mounted in the plug adapted to block said channel so as to lock the firing-pin against forward motion and means on said firing-pin for locking the said centrifugally-operated means until released by the setback 40 due to the firing of the gun.

14. In a fuse, the combination of a casing, a plunger mounted therein so as to be capable of acting forwardly upon lateral impact, a 45 plug mounted in one end of the casing provided with a central channel therethrough, a fulminating-cap mounted in the plug in one end of said channel, a firing-pin slidably mounted within said channel, a pair of centrifugally-operated wings mounted in the plug adapted to obstruct the channel thereof, and locking the firing-pin against forward motion, and means on said firing-pin for locking said 50 wings until released by the setback due to the firing of the gun.

15. In a fuse, the combination of a casing, a plunger mounted therein so as to be capable of acting forwardly upon lateral impact, a plug mounted in one end of the casing provided with a central channel therethrough, a 60 fulminating-cap mounted in the plug in one end of said channel, a firing-pin slidably mounted within said channel, a pair of centrifugally-operated wings mounted in the plug adapted to obstruct the channel thereof 65

and locking the firing-pin against forward motion, and means on said firing-pin engaging and locking said wings, said pin being adapted to release the same when operated by the setback due to the firing of the gun. 70

16. In a fuse, the combination of a casing, a plunger mounted therein so as to be capable of acting forwardly upon lateral impact, a plug mounted in one end of the casing provided with a central channel therethrough, a 75 fulminating-cap mounted in the plug in one end of said channel, a firing-pin slidably mounted within said channel, centrifugally-operated means mounted in the plug adapted to block the channel so as to lock the firing-pin against forward motion, and a spring mounted on said firing-pin for holding the firing-pin so as to lock said centrifugally-operated means until the pin is retracted by the setback due to the firing of the gun. 80 85

17. In a fuse, the combination of a casing, a plunger loosely mounted therein, a plug provided with a central channel mounted in said casing, a fulminating-cap in the plug, a firing-pin slidably mounted within said channel and 90 provided with a cup-shaped enlargement intermediate of its length, centrifugally-operated means mounted in the plug locking the firing-pin against forward motion, and means mounted on the firing-pin for holding said 95 cup-shaped enlargement in locked relation to the centrifugally-operated means, the firing-pin being operated by the setback due to the firing of the gun to release the cup-shaped enlargement from the centrifugally-operated 100 means.

18. In a fuse, the combination of a casing, a loosely-mounted plunger therein, a plug provided with a central channel mounted in one end of said casing, a fulminating-cap mounted in the plug, a pair of wings mounted in the plug adapted to obstruct said channel and provided with recesses, a firing-pin slidably mounted in said channel of the plug and provided with a cup-shaped enlargement adapted 110 to engage the recesses of the wings to hold the wings in an obstructing position, the said wings locking the firing-pin against forward motion, and means mounted on the firing-pin for holding the cup-shaped enlargement in 115 the recesses of the wings and adapted to yield when the firing-pin is retracted by the setback due to the firing of the gun. 115

19. In a fuse, the combination of a casing, a loosely-mounted plunger therein, a plug provided with a central channel mounted in one end of said casing, a fulminating-cap mounted in the plug, a pair of wings mounted in the plug adapted to obstruct the channel and provided with recesses, a firing-pin slidably mounted in said channel of the plug and provided with a cup-shaped enlargement adapted 120 to engage the recesses of the wings to hold the wings in obstructing position, the said wings locking the firing-pin against forward 125 130

4 motion, and a spring mounted on the firing-pin for holding the cup-shaped enlargement in the recesses of the wings and yielding to the setback due to the firing of the gun.

5 20. In a fuse, the combination of a casing, a loosely-mounted spherical plunger therein, a plug mounted in one end of the casing provided with a central channel therethrough, a fulminating-cap mounted in the plug in one 10 end of said channel, a pair of wings mounted in the plug adapted to obstruct the channel thereof, a firing-pin slidably mounted within said channel, means carried by the firing-pin to lock the wings, and a spring mounted on 15 said firing-pin for holding the locking means of firing-pin in engagement with the wings so as to lock said wings, the spring being retracted and the firing-pin moved rearward to release the wings, said action being caused by 20 the setback due to the firing of the gun.

21. In a fuse, the combination of a casing, a plunger loosely mounted therein, a plug mounted in one end of the casing provided with a central channel therethrough, a fulminating-cap mounted in the plug in one end 25 of said channel, centrifugally-operated means mounted in the plug adapted to block the channel, a firing-pin slidably mounted within said channel, means on the firing-pin to lock 30 the centrifugally-operated means, and a spring mounted on said locking means of firing-pin for holding the firing-pin in engagement with the centrifugally-operated means so as to lock 35 said means until released by the setback due to the firing of the gun.

22. In a fuse, the combination of a casing, a loosely-mounted spherical plunger therein, a plug provided with a central channel mounted in said casing, a fulminating-cap in the plug, a 40 firing-pin slidably mounted within said channel and provided with a cup-shaped enlargement intermediate of its length, centrifugally-operated means mounted in the plug locking the firing-pin against forward motion, and 45 means mounted on the firing-pin for holding said cup-shaped enlargement in engagement with the centrifugally-operated means to lock said means said cup-shaped enlargement being disengaged from the centrifugally-operated means by the setback due to the firing 50 of the gun.

23. In a fuse, the combination of a casing, a loosely-mounted spherical plunger therein, a plug provided with a central channel mounted 55 in one end of said casing, a fulminating-cap mounted in the plug, a pair of wings mounted in the plug adapted to obstruct said channel and provided with recesses, a firing-pin slidably mounted in said channel of the plug 60 and provided with a cup-shaped enlargement adapted to engage the recesses of the wings to hold the wings in obstructing position, the said wings locking the firing-pin against forward motion and means mounted on the firing- 65 pin for holding the cup-shaped enlargement

in the recesses of the wings, said firing-pin releasing the cup-shaped enlargement from the recesses of the wings by the setback due to the firing of the gun.

24. In a fuse, the combination of a casing, a 70 loosely-mounted spherical plunger therein, a plug provided with a central channel mounted in one end of said casing, a fulminating-cap mounted in the plug, a pair of wings mounted in the plug adapted to obstruct the channel 75 and provided with recesses, a firing-pin slidably mounted in said channel of the plug and provided with a cup-shaped enlargement adapted to engage the recesses of the wings to hold the wings in obstructing position, the 80 said wings locking the firing-pin against forward motion, and a spring mounted in the firing-pin for holding the cup-shaped enlargement 85 from the recesses of the wings, said firing-pin releasing the cup-shaped enlargement 90 from the recesses of the wings by the setback due to the firing of the gun.

25. In a fuse, the combination of a casing, a loosely-mounted plunger therein capable of acting forwardly upon lateral impact, a plug 90 mounted in one end of said casing provided with a central channel, a fulminating-cap mounted in the plug, a disk mounted in the casing and held in place by the plug and provided with a central opening in alignment 95 with the channel of the plug, a firing-pin slidably mounted in the channel of the plug and guided in its movement by the disk, centrifugally-operated means mounted in the plug for locking the firing-pin against forward motion 100 and means on said firing-pin within the channel of the plug locking said centrifugally-operated means until released by the setback due to the firing of the gun.

26. In a fuse, the combination of a casing, a 105 loosely-mounted spherical plunger mounted therein, a plug mounted in one end of said casing provided with a central channel, a fulminating-cap mounted in the plug, a disk mounted in the casing and held in place by the plug 110 and provided with a central opening in alignment with the channel of the plug, a firing-pin slidably mounted in the channel of the plug and guided in its movement by the disk, centrifugally-operated means mounted in the 115 plug for locking the firing-pin against forward motion, and means on said firing-pin within the channel of the plug locking said centrifugally-operated means until released by the setback due to the firing of the gun. 120

27. In a fuse, the combination of a casing, a loosely-mounted spherical plunger therein, a plug mounted in one end of said casing provided with a central channel, a fulminating-cap mounted in the plug, a disk mounted in 125 the casing and held in place by the plug and provided with a central opening in alignment with the channel of the plug, a firing-pin slidably mounted in the channel of the plug, and guided in its movement by the disk, a pair of 130

- wings pivotally mounted in said plug adapted to be operated by centrifugal force, said wings being adapted to lock the firing-pin against forward movement, and means on said 5. firing-pin within the channel of the plug for locking the wings until released by the setback due to the firing of the gun.
28. In a fuse, the combination of a casing, a plunger mounted therein so as to be capable of 10 acting forwardly upon lateral impact, a plug mounted in one end of said casing provided with a central channel, a fulminating-cap mounted in the plug, a disk mounted in the casing and held in place by the plug and provided with a central opening in alignment with the channel of the plug, a firing-pin slidably mounted in the channel of the plug and guided in its movement by the disk, a pair of wings pivotally mounted in said plug adapted to be 15 operated by centrifugal force, said wings being adapted to lock the firing-pin against forward movement, and means on said firing-pin within the channel of the plug for locking the wings until released by the setback due to the 20 firing of the gun.
29. In a fuse, the combination of a casing having one end open, a plunger loosely mounted in the casing so as to be capable of acting forwardly upon lateral impact, a plug mounted 25 in the open end thereof and provided with a central channel, a circular disk mounted in the casing and held in place by the plug, said disk being provided with an opening in line with the central opening of the plug, a fulminating-cap mounted in the plug, a pair of wings pivotally mounted within the plug adapted to obstruct the central channel, a firing-pin slidably mounted within the central channel of the plug guided in its movement by the opening of the disk, said wings being arranged to lock the 30 firing-pin against forward motion, a cup-shaped enlargement carried by the firing-pin intermediate of its length adapted to engage and lock the said wings, and a spring mounted upon the firing-pin adapted to engage the said enlargement and the circular disk so as to hold 35 the enlargement in locked position with relation to the wings, the cup-shaped enlargement being released by the setback due to the firing of the gun.
30. In a fuse, the combination of a casing having one open end, a loosely-mounted spherical plunger in the casing, a plug mounted in the open end thereof and provided with a central channel, a circular disk mounted in the 40
- 45
- 50
- 55
- 60

casing and held in place by the plug, said disk being provided with an opening in line with the central opening of the plug, a pair of wings pivotally mounted within the central channel of the plug and guided in its movement by the opening of the disk, said wings being arranged to lock the firing-pin against forward motion, and means on the firing-pin for locking said wings until released by the setback due to the firing of the gun.

31. In a fuse, the combination of a casing having one open end, a loosely-mounted spherical plunger in the casing, a plug mounted in the open end thereof and provided with a central channel, a circular disk mounted in the casing and held in place by the plug, said disk being provided with an opening in line with the central opening of the plug, a pair of wings pivotally mounted within the central channel of the plug and guided in its movement by the opening of the disk, said wings being arranged to lock the firing-pin against forward motion, a cup-shaped enlargement carried by the firing-pin intermediate of its length adapted to engage and lock the said wings, and a spring mounted upon the firing-pin adapted to engage the said enlargement and the circular disk so as to hold the enlargement in locked position with relation to the wings, the cup-shaped enlargement being released by the setback due to the firing of the gun.

32. In a fuse, the combination of a casing, a loosely-mounted plunger therein capable of acting forwardly upon lateral impact, a fulminating-cap, a firing-pin, centrifugally-operated means locking the firing-pin against forward motion, and means for locking said centrifugally-operated means until released by the setback due to the firing of the gun.

In testimony whereof I affix my signature in presence of two witnesses.

JAMES L. BROWN.
